W. GRAH.
AUDIBLE LOW LIQUID LEVEL ALARM.
APPLICATION FILED OCT. 4, 1920.

1,371,365.

Patented Mar. 15, 1921.

UNITED STATES PATENT OFFICE.

WILLIAM GRAH, OF WATERVILLE, OHIO.

AUDIBLE LOW-LIQUID-LEVEL ALARM.

1,371,365.

Specification of Letters Patent. Patented Mar. 15, 1921.

Original application filed May 6, 1920, Serial No. 379,232. Divided and this application filed October 4, 1920. Serial No. 414,632.

To all whom it may concern:

Be it known that I, WILLIAM GRAH, a citizen of the United States, and a resident of Waterville, in the county of Lucas and State of Ohio, have made an Invention Appertaining to Audible Low-Liquid-Level Alarms; and I do hereby declare the following to be a full, clear, and exact description of the invention, such as will enable others skilled in the art to which it appertains to make and use the same, reference being had to the accompanying drawings and to the characters of reference marked thereon, which form a part of this specification.

This invention relates to audible alarms for use particularly in connection with the liquid containing tanks of automobiles to indicate a predetermined low liquid level therein.

The object of the invention is the provision of an improved simple and efficient signal or alarm means of the class described, which is operable by movements of the associated vehicle to sound an audible alarm when the liquid in the container is at a predetermined low level therein.

The invention is fully described in the following specification, and while, in its broader aspect, it is capable of embodiment in numerous forms, a preferred embodiment thereof is illustrated in vertical section in the accompanying drawing, with the liquid at a low level point in the tank and the signal means operative.

This application is filed as a division of my former application, Serial No. 379,232, filed May 6, 1920.

Referring to the drawings, 1 designates a liquid tank or container, for instance the gasoline tank of an automobile, having an opening 2 in its top through which the tank may be filled, which opening is closed by a removable cap 3.

Fixedly carried by the cap at its outer side is a bell, gong or other resonant member 4, which, in the present instance, is in inverted position. A rod 5 extends from above the bell 4 down through the same centrally thereof and through the cap 3 into the container 1 and carries a float 6 at its lower end. The rod 5 is mounted for free vertical movements through its bearing in the cap 3 to permit it to move vertically with the float 3 when rising or falling with the change of level of the liquid in the tank. The rod is preferably made in sections with-

in the tank, the sections being connected by a turn-buckle 7 to facilitate an adjustment of the length of the rod to suit the level of the liquid at which it is desired to sound the alarm, as hereinafter more fully described. The rod 5 is preferably provided at its upper end with a bowed portion 8, and from the upper free end of this bowed portion is swingingly suspended a striker 9 so that when the striker is disposed at a predetermined point within the bell 4 and is swung sufficiently to have contact with the bell an alarm will be sounded. A tube 10 projects down from the cap 3 loosely around the rod 5 to prevent liquid when splashing within the tank from escaping through the rod receiving opening in the cap.

It is evident in the use of this invention that the striker 9 is moved into and out of operative striking relation to the gong or bell 4 by the rising and falling of the float within the tank, which is effected by a changing of the level of the liquid therein. When the liquid has lowered a predetermined extent the striker will then be permitted in its swinging movements, which are actuated by jolting movements of the associated vehicle, to strike the bell or gong, thereby sounding an audible alarm to notify the person driving the machine that the liquid supply in the tank should be replenished. If it is desired to change the liquid level at which the alarm is sounded, this may be accomplished by adjusting the turn-buckle 7 to change the length of the float rod.

I wish it understood that my invention is not limited to any specific construction, arrangement or form of the parts, as it is capable of numerous modifications and changes without departing from the spirit of the claims.

Having thus described my invention, what I claim as new, and desire to secure by Letters Patent, is,—

1. In a vehicle, a liquid containing tank, a resonant member mounted without the tank, a striker associated with the resonant member and operable by movements of the vehicle to strike the member and sound an alarm when the striker is in a predetermined position, and means carrying the striker and operable by a change of the liquid level within the tank to move the striker into and out of operative striking relation to the resonant member.

2. In a vehicle, a liquid containing tank, a resonant member carried by the tank, a float supported by liquid in the tank, a rod rising from the float for vertical movements 5 relative to the tank adjacent to the resonant member, and a striker member carried by the rod having free swinging movements relative thereto, and movable into and out of striking relation to the resonant member by predetermined vertical movements of the rod.

3. In a vehicle, a liquid containing tank having an opening in its top, a cap for closing said opening, a resonant member carried by the cap at its outer side, a rod projecting through the cap for longitudinal movements relative thereto, a float attached to the lower end of the rod for riding on liquid contained in the tank, and a striker 20 carried by the rod without the cap and

movable into and out of striking relation to the resonant member by predetermined vertical movements of the rod.

4. In a vehicle, a liquid containing tank having an opening in its top, a removable 25 cap closing said opening, a resonant member rigidly mounted on the cap at its outer side, a float within the tank, a rod carried by and projecting from the float through the cap for vertical movements with the 30 float, the rod being adjustable to vary its length, and a striker swingingly suspended from the outer end of the rod for striking engagement with the resonant member when the liquid is at or below a predetermined 35 level in the tank.

In testimony whereof I have hereunto signed my name to this specification.

WILLIAM GRAH.
